UNITED STATES PATENT OFFICE.

EDWARD W. ISOM, OF WINNETKA, ILLINOIS, AND JOHN E. BELL, OF BROOKLYN, NEW YORK, ASSIGNORS TO SINCLAIR REFINING COMPANY, OF CHICAGO, ILLINOIS, A CORPORATION OF MAINE.

APPARATUS FOR CONDENSING VAPORS.

Application filed June 23, 1921. Serial No. 479,796.

Our invention is more particularly designed for the condensation of vapors from petroleum pressure stills and will be herein-after described in reference thereto, though it will be evident from what follows that in certain of its features it is applicable to the condensation of other vapors. In our improved form of condenser the vapors are condensed by being injected into a body of liquid of the same general composition as the vapors themselves, preferably previously formed condensate. The body of condensate is preferably cooled by means of cooling coils or the like through which circulates a cooling fluid preferably oil or water, the condensate being rapidly circulated in contact with the coils by means to be herein-after described. In the preferred form of the invention fractional condensation is accomplished whereby any desired number of condensates, differing from each other with respect to volatility are formed. This is accomplished by employing a series of condensers maintained at successively decreasing temperatures, the vapors passing first through the condenser in which the condensate is maintained at the highest temperature and thence through the other condensers in the order of their temperatures; thus the condensates in the respective condensers correspondingly differ in the volatility of their components. The differences in temperature between the respective condensers is maintained by circulating the cooling medium in the reverse direction to the circulation of the vapors through the series of condensers thus the vapors coming to the first condenser are at full still temperature say of 550 degrees and are cooled in said condenser to say 400 degrees whereby the least volatile of the components are condensed. In this condenser also the cooling fluid, whether water or oil, inside the cooling coils is at the maximum temperature and if water is employed and at atmospheric pressure it may be discharged at a temperature of 212 degrees or if higher pressure is employed in the cooling coils it may be discharged at a higher temperature and in either event it is suitably preheated for use in boilers or for other purposes. In the second condenser the temperature of the vapors may be reduced to say 250 degrees F., causing the condensation in such condenser of the group of hydro-carbons of the next higher degree of volatility. The water in the coils in this chamber would, of course, be somewhat cooler than that in the coils of the first condenser. In the third condenser which, in the construction shown is the last, the vapors and distillate may be cooled to within a few degrees of the temperature of the entering water. It will thus be seen that the vapors pass to condensers of successively lower temperatures and the water or other cooling fluid to condensers of successively higher temperatures, the flow of water and vapor being respectively in opposite directions. Furthermore, the pressure of the vapors may be correspondingly reduced in the series of condensers, the full still pressure of say 100 pounds being reduced to say 70 pounds in the first condenser, then dropping to 35 or 40 pounds in the second condenser and finally to atmospheric pressure in the third condenser. Any vapor escaping as such with the fixed gas from the third condenser may be condensed in any ordinary manner.

In the accompanying drawings we have shown and in the following specification described preferred forms of the invention. It is to be understood, however, that the specific disclosures are for the purpose of exemplification only and that the scope of invention is defined in the following claims in which we have endeavored to distinguish it from the prior art so far as known to us without, however, relinquishing or abandoning any portion or feature thereof.

In the drawings Fig. 1 is a side elevation partly in section of the preferred form of the invention; Fig. 2 a section on the line 2—2 of Fig. 1; Fig. 3 a side elevation, partly broken away, of a modified form of the apparatus; Fig. 4 a transverse section of the same on the line 4—4 of Fig. 3, and Fig. 5 an enlarged vertical sectional view of a detail.

Each part is identified by the same reference character wherever it appears in the several views. Referring first to the form of the invention shown in Figs. 1, and 2 the condenser shown therein is designed for three stage fractional condensation, there being three condensing units, 6, 7, 8, though obviously a lesser or greater number of units might be employed if desired. As will presently appear these units are connected

up in series, the vapors from the still being first received into the lower condenser and then successively into the middle and upper condensers. The condensers, or the contents thereof, are cooled by coils through which is circulated some cooling liquid which may be water or crude oil on its way to the still, the condenser, in case the latter fluid is used, serving as a preheater for the still.

Except in the respects specifically pointed out the condensing units are identical and the description of one will therefore serve for all. Each preferably comprises a cylindrical drum or shell 9 with closed ends 10, 11, adapted to be partially filled with oil, preferably to about the height indicated by the dotted line 10^a in Figure 2. A closed circuit for providing a forced circulation of the oil in the condenser is provided by a pair of downwardly extending hollow legs 11^a, 12, connected by and communicating with the tank and with a longitudinal pipe 13 which is closed at its ends as at 14, 15. The vapors coming from the still (not shown) are introduced into the pipe 13 at one end thereof by a pipe 16 connected to the still. Pipe 16 communicates with a nozzle 17 secured in the head 15 and extending longitudinally of the pipe 13 so that the vapors coming from the still enter the pipe 13 in the direction of its length and, being under high pressure, with great velocity. The injection of the vapors therefore creates a rapid circulation of the oil from the drum down the hollow leg 12 through the pipe 13 and up the hollow leg 11^a back to the drum. In the drum the oil circulates from the leg 11^a to the leg 12. The injected vapors are thoroughly and intimately mixed and intermingled with the oil in the pipe 13 and also are brought into contact with the oil in the drum. A portion of the vapors are condensed and incorporated with the condensate in the drum but the lighter portions bubble up through the oil in the condenser to the vapor space above the same.

The liquid in the respective drums is cooled by means of coils 18 through which flows a stream of water, crude oil or other cooling medium. The cooling coils 18 are preferably in the form of flat involutes substantially filling the cross section of the condenser, arranged at suitable intervals therein and connected together in series. In each condenser the cooling fluid enters the end coil remote from the end of the drum which first receives the incoming vapors so that the flow of the cooling medium through the condenser is in the opposite general direction to that of the vapors and oil. The first coil in the top-most condenser is connected to some outside source of cooling medium through a pipe 19. The final coil therein is connected by a pipe 20 to the first coil of the second condenser. The cooling liquid flows through the coils of the second condenser escapes through pipe 21 to the inlet 22 of the initial coil of the third condenser and after flowing through the coils thereof escapes through the outlet 23. Each drum is provided with a vapor outlet pipe 24 communicating with the vapor space thereof and connected to the vapor injector pipe 16 of the drum next above, so that the uncondensed vapors from each drum are injected into the circulation pipe 13 of the drum next above and after being thoroughly mixed with the oil in said pipe enter the condensing drum, the uncondensed vapors escaping into the vapor space thereof. The uppermost condenser is provided with an outlet 26 for the fixed gases. Each drum is also provided with a safety valve 27 to maintain any desired pressure thereon and permit the escape of gases and vapors when the pressure which it is designed to carry is exceeded. A draw-off pipe 27^a extends from the bottom of each condenser whereby the condensate may be drawn off continuously or from time to time as desired.

The operation of our improved condenser has been described in connection with the construction thereof but may be briefly reviewed as follows: Assuming that the condensing drums are partially filled with condensate, the vapors from the still injected into the circulation tube of the lowest drum mingle intimately with the condensate therein and force a violent circulation of the mixture in the direction of the arrow *a*. This causes a suction of the liquid from the drum through the hollow leg 12 as indicated by the arrow *b* and a movement of the oil longitudinally of the drum from left to right. The mixture of vapors and condensate, the latter including that from the incoming vapors, enters the drum through the hollow leg 11^a, the uncondensed vapors escaping into the vapor space above the condensate in the drum. The condensate and likewise the vapors are more or less cooled passing lengthwise of the drum and a further condensation is effected therein. From the right hand end of the drum the vapors escape and are injected into the circulation pipe 13 of the next drum where a similar action takes place but at a somewhat lower temperature, the uncondensed vapors escaping to the third drum and so on. The flow of cooling fluid through the coils as heretofore pointed out is in the reverse direction to the flow of the vapors through the drums thus most efficiently using the cooling liquid and bringing it to the highest temperature at the lowermost drum where the vapors are hottest, and in case oil is the cooling medium used it is then at a suitable temperature for introducing into the still. If water be the cooling medium it is thus pre-heated for boiler use. By reason of the decrease in temperature

from drum to drum the condensates from the several drums will be lighter in the order of the drums from the bottom up and, as it is possible by the cooling system shown and described to maintain a well defined difference in temperatures between the successive drums the separation or cut of the groups of hydro-carbons in the respective shells will be correspondingly clean.

10 In Figs. 3, 4, and 5 we have shown a single condenser of a slightly different construction but the mode of operation is the same as that of the condensers shown in Figs. 1 and 2, and if fractional or multiple condensation is desired a plurality of these condenser units may be employed as in the form first described. In this form of the device the condenser drum 30 is likewise provided with a closed circuit 31 for the circulation of the oil, the ends of the circuit, however, entering the ends 32 of the drum. A T 33 is connected to the longitudinal pipe 34 at one of the latter and receives oil from the drum through the branch 35. Vapor pipe 36 coming from the still is secured to cap plate 37 on the T and a nozzle 38^a having a reduced outlet 39^a is connected to the plate 37 to receive the vapors from the pipe 36 and direct them into the pipe 34 in an axial direction. The cooling coils 38, 39, 40 are arranged longitudinally of the condenser, the inlet and outlet pipes 41, 42 thereof being carried through the cover plate 43 of the man hole opening 44. A safety valve may be installed at 45 and a sight glass at 46 to observe the level of the oil. The charging opening for a cleaning or a flushing liquid is shown at 47 and an outlet for the same at 48. These openings are normally closed by cover plates. The usual draw-off outlet is shown at 49. As the operation of this form of condenser is substantially that of the form first described it is unnecessary to repeat the description thereof.

45 We claim:

1. In apparatus of the class described, a

plurality of closed condensing tanks arranged in series, each adapted to contain a body of condensate and a body of vapors above the same, cooling means arranged in 50 each of the tanks means including an expansion nozzle connected with the vapor space of each of the tanks in the series except the last, for injecting vapor into the succeeding tank adapted to introduce the vapors into 55 the body of condensate therein, and means for separately drawing off the condensate from each of said tanks.

2. In apparatus of the class described, a series of condensing tanks each adapted to 60 contain a body of condensate and a body of vapor and gas, means for injecting vapor into the body of condensate in the first of said condensers, means for conducting gas and vapors from the vapor space of each of 65 said condensing tanks and injecting it into the body of condensate in the next tank in the series, means for drawing off the condensate from each of the tanks, a cooling coil in each tank, the cooling coils in the re- 70 spective tanks being connected, and means for supplying cooling fluid to said coils in series the cooling fluid progressing from condenser to condenser in a direction opposite to that of the vapors. 75

3. In apparatus of the class described, a series of closed condensing tanks, a cooling coil in each condensing tank, a circulating system connected with each condensing tank, means for injecting vapors into the circulating system of each condensing tank to force the liquid therethrough, said means, except that connected to the first tank of the series, communicating with the vapor space of the preceding tank, connections between 80 the cooling coils in the respective tanks, and means for circulating fluid through said coils in a direction reverse to the circulation of the vapors through said condensing tank. 85
